SUCTION NOZZLE

Axel Albert Forsberg, Stockholm, Sweden, assignor to Electrolux Corporation, New York, N. Y., a corporation of Delaware

Application November 13, 1944, Serial No. 563,198
In Sweden June 2, 1944

1 Claim. (Cl. 15—416)

1

My invention relates to nozzles and particularly to nozzles for use in connection with a vacuum cleaner in which the nozzles are provided with several openings of different sizes which may be selectively connected to the source of suction. When a larger opening is in use, it will cover a larger surface thereby increasing the speed of cleaning. However, if a concentrated suction is desired in order to remove dirt which the larger opening will not pick up, a smaller opening may be brought into use.

The objects and advantages of my invention will be apparent from the following description considered in connection with the accompanying drawings which form part of this specification, and of which—

Fig. 1 is a perspective view of a nozzle according to my invention, connected to a vacuum cleaner known per se;

Fig. 2 is a cross-sectional view taken on the line 2—2 of Fig. 3;

Fig. 3 is a cross-sectional view taken on the line 3—3 of Fig. 4; and

Fig. 4 is a plan view with the cover of the nozzle partially removed.

Referring to Fig. 1, reference character 10 designates a vacuum cleaner and 11 a flexible suction conduit connected with the suction side of said vacuum cleaner. To this suction conduit a tubular rigid, preferably metallic part 12 is connected which serves as a handle or wand, when the nozzle is passed back and forth over a floor or other surface, the operator normally standing erect and grasping the upper end of handle 12. A portion, here shown as the upper portion of the handle or wand 12 is angularly disposed to form a manipulating extension by which the handle or wand may be turned on its axis and with respect to the nozzle body to control the air passages as hereinafter set forth. To said handle, a nozzle 13 is connected.

Referring to Figs. 2, 3 and 4, the hollow nozzle body 13 includes two parts, an upper nozzle member 14 and a lower nozzle member 15, preferably made of synthetic resin or a light metal alloy, which are connected by screws 16. Between the nozzle parts 14 and 15 is formed a valve chamber in which a hollow valve housing member 17, formed as a T-piece, is pivotally secured within the confines of the body with its opposite cylindrical ports 18 and 19 pivotable in bearings 20 and 21 in the nozzle parts 14 and 15. These two ports 18 and 19, respectively are connected to a smaller suction opening 22 and a larger one 23 by passageways 25 and 24, the junction of the

2

passageways constituting a valve chamber formed by the parts 14 and 15. As will be seen from Figs. 2 and 3, both the suction openings are in the same plane and thus are simultaneously in operative position, that is directed towards the surface undergoing cleaning. The larger suction opening 23 is used for ordinary cleaning, while the smaller suction opening 22 is adapted to be used when picking up articles, as hairs, threads and the like, which tend to adhere especially strongly to the surface to be cleaned.

In order to enable either of the nozzle openings 22 or 23 to be selectively used, in the central branch 26 of valve housing 17, a valve member 27 is provided which, when rotated coaxially with the handle or wand of the suction conduit, selectively establishes communication between the vacuum cleaner unit and the two suction openings. Valve member 27, formed as a cylinder with a hemispherical bottom, is provided with a passage 28, opening to the side at an angle of 90° to the upper portion to which the handle or wand 12 is rigidly but releaseably connected. By a spring ring 29 valve member 27 is retained axially in member 17. In the position illustrated in Fig. 3, the air flow will enter through the large suction opening 23 and pass through passageway 24 and branch 19 to canal 28 and thence through handle 12 and suction conduit 11 to the vacuum cleaner 10. By rotating handle or wand 12 and thereby valve member 27 through half a revolution, communication may be selectively established through passage 25 to opening 22 or through passage 24 to opening 23. Regardless of the rotary position of the valve member 27 it may be pivoted on a horizontal axis with pivotal movement of the valve housing 17 in the bearings 20 and 21 so that the handle or wand may be raised or lowered without changing the setting of the valve member.

It will be understood that many different forms of nozzle openings may be employed in the nozzle above described. The present invention is not concerned with the specific form of such openings but merely with the arrangement in a nozzle for accomplishing the purposes set forth.

While I have described a more or less specific embodiment of my invention, it is to be understood that this has been done for the purpose of illustration only and that the scope of my invention is to be determined by the appended claim.

What I claim is:
A vacuum cleaner suction nozzle comprising a body member defining a pair of spaced parallel

suction openings having different cleaning characteristics and including an upper nozzle member and a lower nozzle member, a centrally disposed opening in the upper nozzle member, a pair of suction passageways formed in said body member between said upper and lower nozzle members and extending from said openings to said centrally disposed opening in the upper nozzle member, a T-shaped hollow tubular valve housing, the arms of the T and the stem of the T being hollow interconnected tubing, a pair of bearing surfaces in the suction nozzle adjoining the opening in the upper member and formed in part by the upper nozzle member and in part by the lower nozzle member for holding the arms of the T-shaped valve housing pivotally mounted therebetween one arm of said T being individually directed to connect with one of said pair of suction passageways while the other arm of said T connects with the other of said pair of suction passageways, while the stem of the T-shaped housing extends outwardly through the opening in the upper member, means for holding the upper and lower nozzle members together, a hollow cylindrical valve member having a hemispherical bottom and fitting into the stem of the T-shaped valve housing, resting on the bottom thereof and freely rotatable therein axially

in said stem, an opening in the hemi-spherical bottom selectively movable upon axial rotation of the valve member to communicate with one or the other of the hollow arms of the T-shaped valve housing, and a suction handle connected with said valve member for connecting the valve member to a source of suction, for selectively controlling the rotation of said valve member whereby said source of suction is connected to one or the other of said suction openings and for adjusting the pivotal position of said valve housing without adversely affecting the suction passageways.
